UNITED STATES PATENT OFFICE.

HARRY S. JONES, OF CHICAGO, ILLINOIS, ASSIGNOR, BY MESNE ASSIGNMENTS, TO
CENTRAL TRUST COMPANY OF ILLINOIS, TRUSTEE.

BINDER.

1,129,206.

Specification of Letters Patent. Patented Feb. 23, 1915.

Application filed April 11, 1913. Serial No. 760,452.

To all whom it may concern:

Be it known that I, HARRY S. JONES, a citizen of the United States, residing at Chicago, in the county of Cook and State of Illinois, have invented a new and useful Improvement in Binders, of which the following is a specification.

My present invention relates particularly to binders employed in loose-leaf ledgers, or the like; and the primary object of the invention is to provide a binder-frame which is light, strong and capable of withstanding the stresses to which it is subjected in use.

The invention is illustrated in the accompanying drawings, in which—

Figure 1 represents a broken plan view of a binder embodying my invention; Fig. 2, a sectional view taken as indicated at line 2 of Fig. 1; Fig. 3, a transverse section taken as indicated at line 3 of Fig. 2; Fig. 4, a fragmentary inner face view of the binder-back, this view being shown partly in section; Fig. 5, a fragmentary inner view of one of the post-carrying clamping-members of the binder; Fig. 6, an inner view of a clamping-member of a binder of modified construction; Fig. 7, a plan view of the same, partly in section, the section being taken as indicated at line 7 of Fig. 6; Fig. 8, a plan view of the binder-back in the modified form; Fig. 9, an elevational view of the same, partly in section, the section being taken as indicated at line 9 of Fig. 8; and Fig. 10, a transverse sectional view of the binder whose members are illustrated in Figs. 6 to 9 inclusive.

Referring to Figs. 1 to 4 inclusive, A represents a binder-back, on which are mounted transversely slidable post-carrying clamping members A' and A². B indicates mechanism adapted to expand and collapse the binder in a well understood manner. The clamping members A' and A² are joined by telescoping posts 1 in a well understood manner, these posts being adapted to be engaged by the removable ledger-leaves. The back A comprises an elongated curved plate 2 equipped on its inner or upper surface at opposite sides of a medial line with flanges 3 between which is disposed a screw-rod 4 of the actuating mechanism B. The back is preferably formed of cast aluminum in which are embedded longitudinal rods or wires 5 of high tensile strength. The rods 5 are embedded in enlargements 6 at the

outer sides of the base portions of the flanges 3. The clamping members A' and A² are of angular cross-section. Each comprises a side or vertical portion 7 having an inwardly off-set upper part 7^a; and an in-turned lower flange 7^b which extends over the back A. Suitable guide connections 8 between the back and clamping members are provided in the usual manner. The sides 7 of the clamping members are enlarged at points 7^c; and in said enlarged portions are embedded wires or rods 9 of high tensile strength. The clamping members are likewise of cast aluminum. The wires are embedded in the back and clamping member 70 castings in the casting process, and are so positioned as to resist the tendency of the castings to break in use.

In the construction illustrated in Figs. 6 to 10 inclusive, a similar, but longer, 75 binder is illustrated. This comprises a back A³ and clamping members A⁴ mounted to slide transversely on the back in the usual manner. In this case, the reinforcing wires 5^a and 9^a are positioned as in the former construction, but are only partially embedded in the castings throughout the length of the wires. At intervals, the castings are provided with lugs 10 and 11 through which the wires extend. That is, the wires are 80 wholly embedded in the castings at the points where they pass through the lugs. In this manner, the wires are securely attached to the castings, although not wholly embedded therein. This construction has the advantage that it is unnecessary to adopt any 85 special expedient to prevent the wires from floating out of the molten metal while a casting is being formed, even where very long castings are required. Nevertheless, 90 the wires are properly positioned to impart to the castings a high tensile strength along the lines where high tenacity is required to prevent the castings from being broken in use. Thus, the wires embedded in the 100 clamping members are at lines considerably outside of the axes of the clamping members; and as the mechanism which serves to close the clamping members is ordinarily attached to the end-portions of the clamping members, the tensile members 9 and 9^a are in a position to resist breakage, which would be liable to result from the outward bowing of the clamping members.

A binder constructed in accordance with 110

this invention can be made both light and strong, which are matters of prime importance in ledgers which are apt to be large and heavy and require frequent handling.

5 The foregoing detailed description has been given for clearness of understanding only, and no unnecessary limitation should be understood therefrom.

What I regard as new and desire to set 10 cure by Letters Patent is—

1. In a binder, the combination with a pair of clamping members, of a back on which said clamping members are movably mounted, comprising a cast metal plate having its inner surface equipped with a pair 15 of longitudinally disposed ribs located on opposite sides of the medial line of the plate, enlargements flanking the base portions of said ribs, and reinforcing wires cast 20 in said enlargements.

2. In a binder, the combination with a pair of clamping members, of a back on which said clamping members are movably

mounted, comprising a cast metal plate having its inner surface equipped with a pair 25 of longitudinally disposed ribs whose base portions are flanked by enlargements composed of lugs, and reinforcing wires cast in said lugs.

3. In a binder, the combination with a back, of a pair of clamping members mounted thereon, each clamping member comprising an angular cast metal plate having longitudinally disposed wire cast therein at a central enlarged portion of one of the sides 35 of the member.

4. In a binder, a binder member comprising a cast metal plate with lugs at intervals thereon, and a reinforcing wire cast in such member, the wire being partially embedded 40 in the plate and extending through said lugs.

HARRY S. JONES.
